UNITED STATES PATENT OFFICE.

AUGUSTUS BROWN MORISON, OF JERSEY CITY, NEW JERSEY, ASSIGNOR TO
THE CO-OPERATIVE BUILDING PLAN ASSOCIATION, OF NEW YORK, N. Y.

DESIGN FOR AN EXTERIOR OF A COUNTRY HOUSE.

SPECIFICATION forming part of Design No. 19,491, dated December 17, 1889.

Application filed November 20, 1889. Serial No. 331,027. Term of patent 3½ years.

To all whom it may concern:

Be it known that I, AUGUSTUS BROWN MORISON, of Jersey City, in the county of Hudson and State of New Jersey, have invented and produced a new and original Design for the Exterior of a House, of which the following is a specification, reference being had to the accompanying drawings, forming a part thereof.

10 Figure 1 represents a side elevation of a house showing my design. Fig. 2 is a front elevation of the same. Fig. 3 represents a plan or horizontal section of the first story. Fig. 4 represents a plan or horizontal section 15 of the second story.

Similar letters of reference designate corresponding parts in all the figures.

A house of this design consists of two stories with an attic third story, said second 20 and third stories being represented as within a gable roof extending widthwise of the house, and also within extensions extending to the front and rear of the house. The first story is shown as having upon one of 25 its front corners a porch and at one of its rear corners, adjacent to the rear extension, another porch. The front and rear extensions are at approximate right angles to the gable roof first referred to, and are each provided with a gable roof. At one side of the 30 front extension is a dormer-window opening from the second story and also provided with a gable roof.

A B C designate, respectively, the portions 35 of the house representing the exterior of the

first and second stories and the attic. Said portions represented at the front of the house are partly comprised in an extension D, provided with a gable roof d, and arranged at one side of the middle of the front and partly 40 in a gable roof F extending widthwise the house. At E is illustrated a dormer-window provided with a gable or peaked roof e. This window is shown as arranged at one side of the extension D and extending from the 45 roof F. The roof F extends downwardly at one side of the extension D to about the top of the first story, and is generally at right angles to the extension D. At one of the front corners of the first story and beneath 50 the dormer-window E, I have shown a porch G. The extension D extends along one side of said porch. Extending rearwardly from the gable roof F is an extension I, likewise 55 provided with a gable roof. This extension is at approximate right angles to the gable roof F, but, as shown, is somewhat lower than the extension D. To the rear of a portion of the first story and at one side of the extension I is a porch J.

60 The various sides of the house have approximately flush exteriors.

What I claim is—

The design for the exterior of a house, substantially as herein shown and described.

AUGUSTUS BROWN MORISON.
